UNITED STATES PATENT OFFICE.

SILAS WRIGHT EMORY, OF WASHINGTON, MISSOURI.

BLACKING-BRUSH.

SPECIFICATION forming part of Letters Patent No. 789,318, dated May 9, 1905.

Application filed July 13, 1904. Serial No. 216,400.

To all whom it may concern:

Be it known that I, SILAS WRIGHT EMORY, a citizen of the United States, residing at Washington, in the county of Franklin and State 5 of Missouri, have invented a new and useful Blacking-Brush, of which the following is a specification.

This invention relates to implements for applying the polishing compound to shoes, and 10 has for its object to simplify and improve the construction and produce a device of this character which may be inexpensively manufactured, easily charged with the blacking compound, and by means of which the compound 15 may be applied to the shoe uniformly and without danger of soiling the fingers.

With these and other objects in view, which will appear as the nature of the invention is better understood, the same consists in certain 20 novel features of construction, as herein-after fully described and claimed.

In the accompanying drawings, forming a part of this specification, and in which corresponding parts are denoted by like designating 25 characters, is illustrated the preferred form of the embodiment of the invention capable of carrying the same into practical operation, it being understood that the invention is not necessarily limited thereto, as various changes 30 in the shape, proportions, and general assemblage of the parts may be resorted to without departing from the principle of the invention or sacrificing any of its advantages.

In the drawings thus employed, Figure 1 35 is a longitudinal sectional elevation, and Fig. 2 is a bottom plan view, of the improved implement. Fig. 3 represents a sectional view of a modified construction of the body portion of the device.

The improved implement comprises a stock 40 or body portion 10, having a handle 11 attached at one side and with a longitudinal recess 12 opening rearwardly and threaded at 13 exteriorly of the open end. A transverse 45 recess 14 intersects the longitudinal recess near the forward end of the stock 10, and arranged in said recess 14 is a revoluble brush 15.

Between the brush-recess 14 and the longitudinal recess 12 is a plate or partition 16, ex-

tending partially across the inner end of the 50 longitudinal recess to partly close it, as hereinafter explained.

Fitting the longitudinal recess 12 is a tubular member 17 for holding the blacking and formed with the edges of the inner or discharge end 18 relatively sharp and bearing 55 against the stop 16 and the outer end provided with an annular flange 19 bearing against the outer end of the stock 10. A threaded cap 20 fits over the threaded end of the stock 60 and serves the twofold purpose of a closure to the aperture 12 and the tubular receiver 17, but also holds the receiver in position by bearing upon the flange 19.

Within the tubular receiver 17 a weighted 65 follower member 21 is free to move and presses upon the blacking material within the receiver.

To charge the receiver with its supply of blacking, the cap 20 is detached, the tubular 70 receiver 17 removed, and its sharpened discharge end 18 pressed into a mass of the blacking material, which cuts out a "core" of the material and leaves it within the receiver, and by repeating the operation the receiver 75 is soon filled and the follower 21 is forced in through the flanged end 19. The receiver is then returned to the recess 12 and the cap 20 restored.

When the implement is to be employed, a 80 shaking motion is imparted longitudinally to the stock, which will cause the relatively heavy follower 21 to drive a portion of the material over the stop-plate 16 and into position to be "taken up" by the brush 15 as it 85 rotates.

In using the implement the brush 15 is drawn back and forth over the shoe, which action causes the brush to "pick up" and uniformly spread the blacking to all parts of the 90 shoe and without waste of material or endangering the cleanliness of the operator, as the handle member 11 is the only part with which the hands come in contact.

The blacking material being confined within 95 the tubular receiver is protected from the action of the air and will retain its semiliquid condition and in the best possible condition

for application to the shoe. When the blacking is exhausted, the receiver can be quickly recharged, as before.

The follower 21 will preferably be of lead 5 or similar heavy material to facilitate its propelling action on the material in the receiver.

The transverse stop 16 is an important feature of the invention, as the area of the discharge from the receiver is thereby reduced 10 and excess of supply to the brush obviated. The stop-plate also serves as a support against which the inner end of the receiver rests to increase the steadiness with which the receiver is held.

15 Attached to the inner side of the stock 10 is a small brush 22 to serve as a preliminary cleaner to remove adhering mud and other foreign matter from the shoe prior to the application of the blacking.

20 A flexible polishing-strip 23 is connected by its ends, respectively, to the forward end of the stock 10 and a block 24 upon the handle 11, as by clamp-plates 25 26 and screws 27 28, the polishing-strip being stretched taut, as required.

25 A pad 29, of felt or other suitable compressible material, is inserted between the block 24 and strip 23 to sustain the latter and increase its efficiency.

30 Several thicknesses of the fabric 23 are employed, so that when one becomes soiled or worn it can be cut loose and the next thickness used, and when all are worn out the polisher may be readily renewed, as will be obvious, 35 by attaching a new stock of the polisher-strips.

Under some circumstances the tubular member 17 may be dispensed with and the blacking inserted directly into the cavity 12 in the stock 10, this modified construction being 40 shown in Fig. 3; but this would not be a departure from the principle of the invention, as the same results would be accomplished in substantially the same manner.

Having thus described the invention, what 45 is claimed is—

1. In a device of the class described, a recessed casing having a magazine or reservoir provided with a contracted discharge-opening, and a revoluble brush partly housed in the recess and arranged adjacent to said discharge-opening.

2. In a device of the class described, a casing having a longitudinal recess open at one end and intersected at its other end by a transverse recess, a blacking-receiver for detachable insertion in said longitudinal recess, a brush mounted for rotation in said transverse recess, and a follower in said receiver and bearing by gravity upon the blacking to force 55 it against the brush.

3. In a device of the class described, a casing having a longitudinal recess open at one end and intersected at its other end by a transverse recess, a blacking-receiver for detach-

able insertion in said longitudinal recess, a 65 brush mounted for rotation in said transverse recess, a stop-plate extending transversely of the discharge end of said receiver and reducing the area of the same, and means operating in said receiver for forcing the blacking over 70 said stop-plate and against the brush.

4. In a device of the class described, a casing having a longitudinal recess open at one end and intersected at its other end by a transverse recess, a brush mounted for rotation in 75 said transverse recess, a blacking-receiver for insertion in said longitudinal recess and having parallel sides and open at one end with the edges of the open end relatively sharp to facilitate the insertion of the blacking, and 80 means operating in said receiver for forcing the blacking therefrom upon the brush.

5. In a device of the class described, a casing having a longitudinal recess open at one end and intersected at its other end by a transverse recess, and threaded exteriorly of said 85 open end, a blacking-receiver for insertion in said longitudinal recess and with an annular flange engaging the threaded end of the casing, a threaded cap engaging said threaded 90 end and bearing upon said flange, a brush mounted for rotation in said transverse recess, and means operating in said receiver for forcing the blacking therefrom against the brush.

6. In a device of the class described, a casing having a longitudinal recess open at one end and intersected at its other end by a transverse recess, and threaded exteriorly of said 95 open end, a blacking-receiver for insertion in said longitudinal recess and with an annular flange engaging the threaded end of the casing, a threaded cap engaging said threaded end and bearing upon said flange, a brush mounted for rotation in said transverse recess, a stop-plate extending transversely of the discharge end of the receiver and extending partially across the same to reduce the discharge area and against which the receiver is held by the screw-cap.

7. In a device of the class described, a casing having a longitudinal recess open at one end and intersected at its other end by a transverse recess, a blacking-receiver for detachable insertion in said longitudinal recess, a brush mounted for rotation in said transverse 115 recess, a stop-plate extending transversely of the discharge end of said receiver and reducing the area of the same, and a follower within the receiver and bearing by gravity upon the blacking to force it against the brush.

In testimony that I claim the foregoing as my own I have hereto affixed my signature in the presence of two witnesses.

SILAS WRIGHT EMORY.
